UNITED STATES PATENT OFFICE

2,660,395

COMPRESSIBLE TUBE VALVE

Jesse K. Mair and Christopher J. McNally, Allentown, Pa., assignors to Cement Gun Company, Inc., Allentown, Pa., a corporation of New Jersey

Application November 21, 1949, Serial No. 128,563

2 Claims. (Cl. 251—5)

1

This invention relates to a compressible tube valve structure, and more particularly to valves for the control of abrasive carrying fluid streams.

Ordinary valves comprising metal plugs or gates have been found unsatisfactory for the control of abrasive carrying streams, since the abrasive, often travelling at high velocity, in a short time erodes the valve parts subjected to the action thereof, with the result that after a comparatively short period of service the valves leak or stick, necessitating frequent repairs and replacements.

It is an object of the present invention to provide a valve which will efficiently withstand the wear of an abrasive carrying fluid stream passing therethrough.

It is a further object of this invention to provide a valve comprising a compressible liner adapted to be compressed to control the effective opening thereof.

A further object is to provide a valve comprising a compressible liner which may be readily removed and replaced when worn.

Another object is to provide a valve quickly and positively opened and closed by the action of a lever member.

Yet another object is to provide a valve comprising a substantially fully enclosed compressible liner, permitting the use of high pressures therewith.

Still another object is to provide a compressible liner valve structure adapted for service under dusty and dirty conditions, the valve being inherently self-cleaning of dust and abrasive material finding its way into the operative parts thereof, whereby the life of the liner is greatly extended.

Other objects of the invention will be in part obvious and in part pointed out hereinafter.

The invention and the novel features thereof may best be made clear from the following description and the accompanying drawings, in which:

Figure 1 is a side view of a preferred embodiment of the present invention, with parts shown in open position;

Figure 2 is a longitudinal section of the same, showing the valve in closed and locked position;

Figure 3 is a transverse section taken along the line 3—3 in Figure 1;

Figure 4 is a transverse section taken along the line 4—4 in Figure 2;

Figure 5 is a partial section showing the valve associated with an abrasive material loading hopper;

2

Figure 6 is a longitudinal section showing details of the sleeve forming a part of the valve housing;

Figure 7 is a perspective view of the compressible liner insert of the valve, and

Figure 8 is an elevational view of the valve ball member and follower.

Referring to the drawings, the valve comprises a sleeve 10 of rigid material, preferably metal, provided with an opening 11 in the side thereof, and spaced, parallel lugs 12 projecting from the sleeve on opposite sides of opening 11. Slidably supported between lugs 12 is a follower 13, guided and retained by guides 14 extending from the sleeve intermediate lugs 12, and by the projecting ends of pin 15, engaged in the lug slots 16. The inner end 17 of follower 13 is concave, and bears against and partially encloses a ball 18, as may best be seen in Figures 2, 3, 4, and 8. An actuating lever 19 is pivotally mounted between the ends of lugs 12 by means of pivot 20, and comprises near its pivot end the cam surface 21 and lock surface 22.

Concentrically enclosed by sleeve 10 is the compressible liner insert 23, provided with external end flanges 24. The liner insert 23 is made of suitable compressible, elastic material, such as rubber, synthetic organic plastic, or the like, and its adjacent wall cooperates with follower 13 to retain the ball 18 therebetween. The enlarged end portions 25 of sleeve 10 terminate in annular stop surfaces 26, disposed against the end flanges of the liner insert, and are enclosed by cap members 27. Cap members 27 comprise internal shoulders 28, positioned and adapted to engage the end surfaces of the liner insert and its flanges, and to cooperate with the sleeve stop surfaces 26 to compress the liner insert flanges therebetween to form seals. A plurality of apertured projections 29 extend from the cap fittings, by means of which the cap fittings may be aligned and engaged by bolts 30 and drawn up toward each other. To prevent relative rotation of the cap fittings and bolts when assembled, a stud 31 may extend from sleeve 10, said stud comprising a groove 32 adapted to partially enclose one of the bolts 30 and thereby maintain its relative position. The outer ends of the cap fittings may be threadably engaged to component parts of a fluid carrying system, such as the nipple 33 and pipe 34, illustrated in Figures 1 and 2.

The valve is open when actuating lever 19 is in the position shown in Figures 1 and 3. It will be seen that in this position the passage therethrough is straight and smooth, and contains no

obstructions. The valve is closed by the single motion of lever 19 in an arcuate path about its pivot 20, whereby the flat outer end surface of follower 13 is successively engaged first by the cam surface 21, whereby the follower and ball are progressively moved inwardly causing the ball to compress the adjacent wall of the liner insert until it meets and is compressed against the opposite wall thereof, and then by lock surface 22, which holds the follower and ball firmly in the 10 position shown in Figures 2 and 4. In this position it will be readily seen that the passage through liner insert 23 is effectively closed, and the valve remains in closed position until disengagement of lock surface 22 from follower 13 is 15 effected by manual movement of lever 19. On return of lever 19 to open position, the liner insert is opened by its inherent elasticity and by the internal pressure of the fluid system of which the valve is a part. Desirably, the diameter of ball 18 is slightly less than the internal diameter of the liner insert, so that in engaging the liner insert in closed position as shown in Figure 4, the ball exerts equal pressure thereagainst along the entire arc of contact, insuring full closure of the passage.

Figure 5 shows a typical utilization of the valve of the present invention, employed as an exhaust valve in association with the hopper 35, designed for loading sand or sand-cement mix into machines for the pneumatic application of such materials. Above the hopper 35 is provided a cone valve 36 and the cone valve gasket 37, through which dry sand or sand-cement mix is loaded into the hopper, whereupon the cone valve is closed and the hopper pressurized. The hopper may then be opened to the associated pneumatic mixing and delivery system (not shown), and the charge allowed to drop therewith. The hopper 35 is then closed off from such apparatus and the exhaust valve, indicated generally as 38, opened to relieve the pressure within the hopper, whereupon the cone valve 36 may be opened and another material charge loaded therethrough.

The exhaust valve 38, it will be seen, in this application is periodically subjected to the passage of a high velocity gas stream carrying fine abrasive particles in suspension therethrough. Such service has been found to quickly erode the metal gates or plugs of conventional valves, resulting in but a short period of service before causing leakage, sticking, and other malfunctioning of the valve and associated apparatus.

The exhaust valve of this invention has been found to be particularly useful in this and similar applications, since it opens quickly to its full opening and offers no obstructions to the passage of fluid therethrough. On displacing the actuating lever, the valve immediately flies open, avoiding excessively high velocities therethrough corresponding to partially open position. The liner insert 23, formed preferably of rubber or similar material, has been found to effectively withstand the wear of such usage. In addition, it will be noted that the valve is readily disassembled, without removal from associated apparatus, whereby the liner insert 23 may be quickly and easily replaced, reducing maintenance time and expense to a minimum and substantially eliminating shutdown occasioned thereby. To replace the liner insert, it is necessary only to remove the nuts from one end of the bolts 30, whereupon the cap fittings 27 may be backed off sleeve 10, and the worn liner insert removed and replaced by a new one. The cap fittings may

then be placed over the ends of the sleeve and by means of bolts 30 drawn together to form effective seals with the liner insert flanges 24 between the shoulders 28 of the cap fittings and the stop 5 surfaces 26 of the sleeve.

In the type of service described, it will be readily appreciated that the valve functions in an atmosphere laden with dust and abrasive particles, whereby such air-borne particles are prone to find their way into the valve and cause malfunctioning thereof. Particularly, in valves of this type it has been discovered that such particles are especially prone to collect on the sliding element employed to compress and close the liner insert. In this manner, abrasive material is forced into the adjacent surface of the liner insert and considerable damage results. In fact, grit carried by the compressing member and forced into the exterior surface of the liner insert has been found 20 to cause deterioration and failure thereof more quickly than the action of the abrasive particles passing through the interior thereof.

In the valve of the present invention this deleterious effect is substantially avoided by reason 25 of the self-cleaning action of the follower and ball assembly, it having been found that ball 18 and its follower 13 coact to periodically clean the ball of grit accumulated thereon. The internal fluid pressure exerted against the stoppage in the liner 30 insert when the valve is closed effects a valve opening, when handle 19 is manipulated, approaching a snap action. This opening action, it has been found, effects some rotation of ball 18 relative to its follower each time the valve is 35 opened. The rotation of the ball relative to the follower effects a scraping action therebetween, whereby grit accumulated on the ball surface is loosened and removed, and the portion of the ball forced against the liner insert is thereby maintained substantially free of grit accumulations 40 which would shorten the life of the liner insert.

It will thus be seen that there has been provided by this invention a structure in which the various objects hereinbefore set forth, together 45 with many practical advantages, are successfully achieved. As various possible embodiments may be made of the mechanical features of the above invention, all without departing from the scope thereof, it is to be understood that all 50 matter hereinbefore set forth or shown in the accompanying drawings is to be interpreted as illustrative, and not in a limiting sense.

We claim:

1. A valve comprising a cylindrical compressible liner insert, a rigid sleeve enclosing said liner insert, an opening in said sleeve, opposed lugs extending from said sleeve on opposite sides of said opening, guides disposed adjacent said opening between said lugs, a follower slidably supported between said lugs and guided therebetween for straight line movement normal to the axis of said insert, the inner end of said follower being concave, a ball disposed between the inner end of said follower and said liner insert for movement with the follower, the curvature of the inner end of said follower corresponding substantially to that of said ball whereby said ball may freely rotate relative to the concave end of said follower, the diameter of said ball being slightly less than the internal diameter of said liner insert, and a lever pivotally mounted between said lugs, said lever comprising a cam surface adapted to engage the outer end of said follower and depress said follower 65 and ball to compress said liner insert and close

the passage therethrough, the cam surface being so formed as to effect a quick opening of said valve approaching snap action.

2. A valve as set forth in claim 1, including a lock surface on said lever adjacent said cam surface, adapted to engage and maintain said follower in depressed position.

JESSE K. MAIR.

CHRISTOPHER J. McNALLY.
